UNITED STATES PATENT OFFICE.

THOMAS CURETON, OF DAYTON, OHIO, ASSIGNOR TO THE GAS RESEARCH COMPANY,
OF DAYTON, OHIO, A CORPORATION OF OHIO.

GAS GENERATION.

Application filed May 31, 1921. Serial No. 473,568.

To all whom it may concern:

Be it known that I, THOMAS CURETON, a citizen of the United States of America, residing at Dayton, county of Montgomery, 5 and State of Ohio, have invented certain new and useful Improvements in Gas Generation, of which the following is a full, clear, and exact description.

This invention relates to gas generation, 10 and more particularly to a method of controlling the generation of gas, and apparatus for carrying that method into effect, to deliver a gas of substantially constant characteristics, to a work device.

15 The principal object of the invention is to so control the generation of a gas, having desired characteristics, that those particular characteristics shall be maintained substantially constant.

20 Another object is to so control the generation of producer gas that the number of heat units delivered to a work device shall be maintained substantially constant per unit of time.

25 Another object of the invention is to provide suitable apparatus for carrying out this method of control.

While this invention is generally applicable to any gas making reaction, it has 30 been primarily worked out in connection with the generation of producer, or analogous gas, and the description of the invention set out herein is based upon the application of the invention to the controlling 35 of a gas producer. As illustrative of apparatus for carrying out this method, in the controlling of a gas producer, two forms of apparatus are illustrated, in the accompanying drawing, in which,

40 Fig. 1 is a diagrammatic view partly in section and partly in elevation showing a pressure producer operated by means of a steam jet blower, with controlling apparatus; and,

45 Fig. 2 is a similar view of a suction producer.

In the operation of gas producers a blast 50 of air and moisture is passed through a bed of ignited, or incandescent carbonaceous material, such as coke, anthracite, or bituminous coal. As this blast passes through the incandescent carbonaceous material certain reactions take place resulting in the production of a combustible gas. This blast is normally passed through the producer

either under pressure, as by means of a pressure blower which forces the blast through the generating chamber of the producer and the fuel bed contained therein, or under suction, as by means of a vacuum pump 60 or blower which tends to evacuate the generating chamber and thus causes a flow of air and moisture into the generating chamber and through the fuel bed therein. In either case the gas within the delivery main, 65 which leads the gas to a work device, is under pressure.

It is almost universally desirable, and in many cases practically necessary, that the 70 number of heat units delivered to a work device in the gas be maintained substantially constant. For example, if gas is being burned in a heat treating furnace it is practically essential, for satisfactory operation of the furnace that the temperature 75 therein be maintained within a very short temperature range. With a given valve setting, or given effective opening at the burner, this temperature may fluctuate as a result of either a variation in the pressure of the delivered gas or a variation in 80 its heat value. The inability to control the generation of the gas so as to deliver heat units to each work device at a uniform rate has heretofore necessitated close application of the operator in order to maintain 85 desired conditions within the furnace, or other work device.

In this invention the generation of the 90 gas is so controlled that the number of heat units delivered to a given work device, per unit of time, is maintained substantially constant. This is done by withdrawing a fraction of the generated gas, from the delivery main, through a constant orifice, 95 burning the withdrawn fraction of gas, and increasing or decreasing the quantity of gas generated and delivered to the various work devices according to the heat generated by this burning gas.

In Fig. 1, for example, a producer, or gas generator, is designated generally by the numeral 10. This producer may be of any desired character, the particular producer shown being largely diagrammatic. This 105 producer contains a generating chamber 11 adapted to contain a fuel bed 12, of ignited or incandescent carbonaceous material, such as coal or coke, fresh fuel being introduced through the fuel feeding mechanism 13 and 110

ashes being withdrawn through the open bottom of the machine. The blast, which consists of a mixture of air and moisture, in any predetermined proportions, is introduced into the generating chamber through the blast pipe 14, to which is connected a steam jet blower designated generally by the numeral 15. Steam jet blowers, particularly designed for producer operation, are commercially well known and any of the approved types of such blowers will function satisfactorily. The blower 15 is therefore illustrated diagrammatically, details of construction thereof not being set out.

15 Steam for operating the blower 15 is introduced through the pipe 16, this steam being from any desired source, and under any suitable operating pressure. As the steam passes through the blower air is induced, as indicated by the arrows adjacent the blower, the proportion of air and moisture being substantially constant under given operating conditions, the blast, or mixture of air and moisture being introduced into the generating chamber through the blast pipe 14, and forced upwardly through the fuel bed 12, the gas resulting from the reactions within the fuel bed passing off through the delivery main 20.

30 The gas within the delivery main 20 is under pressure, and is passed, through the main, to any desired place of storage or use. As shown two branch pipes 21 and 22, lead off from the delivery main to furnaces 23 and 24 respectively these furnaces being shown purely in a diagrammatic way, as illustrative of a form of work device adapted for utilizing the generated gas.

The flow of gas into either of the furnaces 40 is normally controlled by means of a valve, not shown since any conventional type of valve suitably placed within each of the branch delivery pipes may be used. This control valve having been set, that is, its effective opening having been once set, any variation in either the delivery pressure or the heat value of the gas will result in an increase or decrease in the number of heat units passing into the furnace, and this will inevitably be attended by temperature fluctuations therein. Variations in pressure may occur as a result of a large variety of circumstances, as for example when the load is increased or decreased, when the resistance within the fuel bed varies, when the pressure of the steam delivered through the pipe 16 varies, etc. Heat value of the gas may vary from a number of different causes, as for example, if fuel of different chemical characteristics is introduced into the generating chamber, or channels are burned in the fuel bed, or the temperature of the fuel bed varies materially without a corresponding variation in the proportion of moisture in the air blast, etc. Various devices have

been, heretofore, devised for the purpose of maintaining the top pressure, in the producer, or, what is substantially the same, the delivery pressure in the delivery main, substantially constant. These devices function with more or less success to accomplish the purposes for which devised, but none of these devices is adapted to control the generation of the gas so that a definite relationship exists between the heat value of the gas and the delivery pressure of the gas.

The purpose of this invention is to provide for thus controlling the gas generating apparatus. Leading off from the delivery main 20 is a pipe 30, to which is attached a burner 31. As shown the burner 31 has the base portion thereof, the portion which is threadedly mounted upon the end of the pipe 30, enlarged and has a diaphragm, having a constant orifice 33, mounted in such enlarged base portion. Inasmuch as the gas in the delivery main 20 is under a pressure in excess of atmospheric pressure, a fraction of the gas will pass from the delivery main through the pipe 30 and the constant orifice 33 to the burner 31. As the orifice 33 is fixed the amount of gas which passes therethrough to the burner will be dependent upon the pressure conditions within the main 20. The burner 31 is located within a combustion chamber 35, air inlet ports 36, for admitting air into the combustion chamber 35 to support the combustion of the gas escaping from the burner, being located in the bottom of the combustion chamber, and a vent or flue opening 37 provided in the top. Positioned within the combustion chamber 35 is a vessel 40 having a pipe 41 connecting the interior of this vessel to the interior of a sylphon or expandable bellows 42. The vessel 40 contains a quantity of vaporizable liquid 43.

The vessel 40 is so positioned that the hot products of combustion of the gas at the burner 31 as they pass upwardly to the vent 37 will contact therewith and vary the vapor pressure within that vessel, and the sylphon bellows 42, according to variations in the heat generated by the burning gas. The lower end of the sylphon bellows 42, which is attached to the pipe 41, is fixed, the upper end being movable, as the bellows expands or contracts, and pivotally attached by means of the link 46, to one end of the lever 46, the other end of which is pivotally attached to some fixed part of the apparatus, illustrated diagrammatically at 47. Pivotally attached to the lever 46 intermediate its ends is a rod 48, the other end of this rod being pivotally connected to the operating arm 49 of the valve 50. The valve 50, which is located within the steam pipe 16, and constructed to control the flow of steam therethrough, is shown diagrammatically, inasmuch as any of the conventional types of

valve may be used in this relation. The rod 48 has a turn-buckle 51 therein for varying its length, to permit of adjustment of the controlling apparatus.

Pressure within the vessel 40 and sylphon 42 is directly responsive to the heat generated at the burner 31. Variations in the heat generated will occur if a greater quantity of gas is burned, even though there be no fluctuation in heat value, or if the heat value fluctuates even though there be no variation in pressure. The amount of gas fed to the burner 31 is dependent upon pressure within the main 20. If that pressure decreases, as, for example, when the load is increased, the amount of gas passing through the constant orifice 33 to the burner 31 will decrease, and, therefore, the heat generated at that burner will also decrease. This will cause a corresponding decrease of pressure within the vessel 40 and sylphon 42. The sylphon will therefore contract, and acting through the lever 46, rod 48, and operating arm 49, will vary the setting of the valve 50 to increase the quantity of steam passing through the pipe 16. Thus the quantity of air and moisture passing through the fuel bed will be increased to increase the quantity of gas generated to bring the pressure within the delivery main up to the predetermined desired point. Or suppose without any variation of the pressure within the delivery main the heat value of the gas varies. As this heat value varies the heat generated at the burner 31 will correspondingly vary, without any variation in the quantity of gas burned, and the valve 50 will be actuated to increase or decrease the quantity of blast. As a consequence the quantity of gas generated will correspondingly increase or decrease to vary the pressure within the delivery main, so that, even though the gas generated thereafter remains of a constant heat value per cubic foot, the quantity of gas passing through the orifice 33 will be varied so that the actual number of heat units delivered to the burner will be brought back to the desired normal.

And the conditions which obtain at the burner 31 are entirely analogous to those which obtain at each work device, as for example at each of the furnaces 23 and 24. For the effective opening of the valve controlling the flow of gas to each of the furnaces 23 and 24 is a fixed orifice, just as is the orifice 33. So by maintaining conditions within the delivery main so that the number of heat units delivered to the burner 31 is maintained constant per unit of time these conditions will also insure the delivery of a constant number of heat units to each furnace, or other work device, per unit of time.

The control apparatus shown in Fig. 2 is identical in principle with that shown in

Fig. 1, and described above. The producer shown for Fig. 2 however is adapted to operate under suction. This producer, which is designated generally by the numeral 100 is adapted to contain a fuel bed of ignited, or incandescent, carbonaceous material 101, within the generating chamber 102, the fuel bed, in this type of apparatus, being supported upon a suitable grate 103, fuel being introduced from time to time as needed through the fuel feeding mechanism 104. The air and moisture, which reacts with the fuel to cause generation of gas, is introduced through the pipe 105, the flow through this pipe being induced under the action of the pump or exhauster 106, the generated gas passing off through the offtake or down-comer 107 into a washer or condenser 108. The details of construction of this washer are not shown, since it may be of any conventional character, the gas being introduced into the washer, through the pipe 107 adjacent the lower end thereof and passing upwardly therethrough to pass off through the pipe 109. While passing through the condenser the gas is subjected to a water spray, which is introduced through the pipe 110. The pipe 109 is connected to the inlet 115 of the pump or exhauster, which as shown is of the gear or impeller type, though any other type of pump may be used if desired. For example, a centrifugal blower will function satisfactorily as a substitute for the impeller pump illustrated.

In the form of apparatus illustrated in Fig. 1 the air, being forced into the producer by means of a steam jet blower, the proportions of air and moisture are automatically maintained, since the quantity of air introduced is proportional to the quantity of steam utilized in forcing that air into the producer. Inasmuch as the producer illustrated in Fig. 2 is suction operated other means must be provided for regulating the proportion of air and moisture introduced to the generating chamber. Any desired type of apparatus for accomplishing this purpose may be used, but a "saturator" of the type illustrated is preferred. This saturator consists of a chamber 120, housing a set of baffles or grids 121, this chamber having its upper end connected to the air inlet pipe 105 its lower end being connected to the atmosphere through the port 122. Leading into the upper end of the saturator is a pipe 123, through which hot water enters and passes downwardly over the grids and out through the discharge opening 124. As the air passes in through the opening 122, upwardly through the grids and out through the pipe 105 into the generating chamber it contacts with this heated water and becomes saturated with moisture at the temperature existing within the saturator. By varying the quantity of hot water intro-

duced into the saturator the temperature within the saturator may be correspondingly varied, and, since the air will become saturated with moisture at the temperature which exists, the proportion of moisture in the blast may be varied. A valve 125 of any suitable type is positioned within the hot water supply pipe, this valve being provided with an operating arm 126 which is pivotally connected to thermostatic apparatus constructed to vary the setting of the valve to maintain any predetermined temperature within the blast supply pipe 105. This thermostatically operated apparatus may be of any desired character, such, for example, as that shown in the patent of Harry F. Smith 1,397,556, dated November 22, 1921, or the patent to Harry F. Smith No. 888,359 dated May 19, 1908. Preferably, however, this apparatus consists of a siphon bellows 127, the interior of which is connected to the air blast pipe by means of the pipe 128, the interior of this bellows thus being subjected to temperature and pressure conditions which are in accordance with the conditions existing within the air supply pipe. The end of this siphon which is connected to the pipe 128 is fixed but the other end is free to move as the bellows expands or contracts. This movable end is operatively connected by means of a pivoted link 129 to a lever 130 one end of which is pivoted to some fixed part of the apparatus as shown diagrammatically at 131. Also pivotally connected to the lever 130 is a rod 132, which is in turn pivotally connected to the operating arm 126 of the valve 125. As the temperature within the saturator, and thus within the blast supply pipe, varies there will be a corresponding variation of temperature within the siphon to actuate the valve 125 to increase or decrease the quantity of hot water passing therethrough into the saturator, to maintain temperature conditions within the saturator substantially constant.

As shown in the drawing the blower 106 is driven by means of an electric motor 135, a belt 136 being utilized for furnishing the driving connection between the motor and blower. Leading off from the delivery main beyond the blower is a pipe 140, to which is connected a burner 31', this burner, as in Fig. 1 having an enlarged base within which is positioned a plate or diaphragm 32' having a constant orifice 33' therein. This burner is also located within a combustion chamber 35' housing the closed vessel 40' to which is connected, through the pipe 41', the siphon bellows 42', air inlet openings 36' and a vent opening 37' being provided as described above in connection with Fig. 1. The vessel 40' also contains a vaporizable liquid 43'. Operatively connected to the movable end of the siphon 42' is a link

145, the opposite end of the link being pivotally connected to a lever 146 which is pivotally mounted upon some fixed part of the apparatus illustrated diagrammatically at 147. Pivotally connected to the other end 70 of the lever 146 is a link 148, which is also pivotally connected to the pivoted member 149, which constitutes the slidable arm of a variable resistance 150, the arm 149 being pivotally mounted upon some fixed part of 75 the apparatus illustrated diagrammatically at 151, and being grounded, as shown. The motor 135 is connected in circuit with any suitable source of electrical energy, illustrated diagrammatically as a battery 160. 80 The variable resistance 150 being positioned within the motor circuit.

The operation of this device is substantially identical with that illustrated above. As the heat generated at the burner 31' 85 varies the siphon expands or contracts, thus, acting through the mechanism associated therewith, varying the positioning of the member 149 to increase or decrease the resistance within the motor circuit to vary 90 the speed of operation of the motor, which in turn varies the speed of operation of the pump or exhauster and thus varies the quantity of gas passed through the delivery main. As a result the number of heat units 95 actually delivered through a fixed orifice connected to the delivery main, such as the orifice 33', or the orifice at any of the valves controlling the various work devices, such as furnaces, will be maintained substantially 100 constant.

In the device illustrated in Fig. 1 the steam jet blower may be dispensed with if desired and a positive blower, such as an impeller pump, or a turbo-blower substituted in lieu thereof. In the case of the turbo-blower the controlling mechanism would actuate the throttle valve to control the speed of operation thereof. And, of course, a turbo-blower could be used with 110 the form of producer shown in Fig. 2. Also, if desired a gear pump driven by a reciprocating steam engine might be used with either type of producer, the exhaust steam from the steam engine serving to supply 115 the moisture within the air blast, in which case the controlling mechanism could be arranged to vary the cut-off of the distributing valve to vary the speed of operation of the engine.

While the method herein described, and the forms of apparatus for carrying this method into effect, constitute preferred embodiments of the invention, it is to be understood that the invention is not limited 125 to this precise method and forms of apparatus, and that changes may be made in either without departing from the scope of the invention which is defined in the appended claims.

What is claimed is:

1. In the generation of gas, in which a blast of air and moisture is passed through a fuel bed of ignited carbonaceous material contained within a generating chamber, the method of controlling the delivery pressure of the generated gas which consists in withdrawing a fraction of said gas through a constant orifice, burning said withdrawn fraction, and controlling the quantity of blast introduced into the generating chamber to accord with the heat generated by such burning fraction.
2. In the generation of gas, in which a blast of air and moisture is passed through a fuel bed of ignited carbonaceous material contained within a generating chamber, the method of controlling the delivery pressure of the generated gas to control the number 20 of heat units delivered in said gas to a work device, which consists in allowing the escape of a fraction of the gas, which fraction is proportional to the delivery pressure of the gas, burning such fraction of gas 25 and controlling the quantity of blast passed through the fuel bed, thus controlling the quantity of gas generated, according to the heat generated by such burning fraction.
3. In the generation of gas, in which a blast of air and moisture is passed through a fuel bed of ignited carbonaceous material contained within a generating chamber, the method of controlling the quantity of blast passed through the fuel bed to maintain a 35 definite relationship between the delivery pressure and the heat value of the generated gas, which consists in withdrawing a fraction of the gas, the quantity of the fraction so withdrawn being proportional to the 40 delivery pressure of the gas, burning such withdrawn fraction, and controlling the quantity of blast to accord with the heat generated by the burning of such withdrawn fraction.
4. In the generation of gas, in which a blast of air and moisture is passed through a fuel bed of ignited carbonaceous material contained within a generating chamber, the method in which the generation of the gas 50 is so controlled as to deliver to a work device a constant number of heat units in the generated gas for a given interval of time, which consists in withdrawing a fraction of the generated gas, which fraction is proportional to the delivery pressure of said 55 gas, burning said withdrawn fraction and controlling the quantity of blast introduced into said generating chamber according to the heat generated by said burning gas.
5. Gas generating apparatus comprising a gas generator adapted to contain a fuel bed of ignited carbonaceous material, means for passing a blast through said generator, and means responsive to variations in both 60 the pressure and the heat value of the gen- erated gas for controlling said blasting means.
6. In gas generating apparatus, a generating chamber adapted to contain material which when caused to undergo a chemical reaction with other suitable material will produce a desired fluid, means for introducing into said generating chamber the material adapted to react therein in the generation 70 of the desired fluid, and means responsive to the pressure and to the composition of the resulting fluid for controlling such introducing means.
7. In gas generating apparatus, a generating chamber adapted to contain a fuel 80 bed of ignited carbonaceous material; means for passing a blast of air and moisture through said fuel bed to cause the generation of gas; and means for controlling said blasting means to regulate the quantity 85 of blast passed through the fuel bed, said controlling means comprising a pipe, containing a constant orifice, connected to the delivery main and to a gas burner, a heat responsive element associated with said 90 burner, and means associated with said heat responsive element to actuate the said controlling means.
8. In gas generating apparatus, a producer constructed to contain a fuel bed of 95 ignited carbonaceous material, a steam jet blower for forcing a blast of air and moisture through said fuel bed to cause the generation of gas, a valve for controlling the flow of steam to said blower, a burner, 100 a pipe connected to the producer, and having a constant orifice therein, through which a fraction of the generated gas may pass to the burner, heat responsive means associated with said burner, and mechanism 105 actuated by said heat responsive means for operating the steam control valve to regulate the quantity of blast passed through the fuel bed according to the heat generated 110 at said burner by the burning gas.
9. In gas generating apparatus, a producer constructed to contain a fuel bed of ignited carbonaceous material, means for passing a blast of air and moisture through said producer and the contained fuel bed 115 to cause the generation of gas, means for controlling the operation of said blasting means, a pipe having a constant orifice therein through which a fraction of the generated gas passes to a burner and heat responsive mechanism associated with said burner and with said blast controlling means, the construction being such that the blasting means will be controlled to accord 120 with the heat generated by the gas burning 125 at said burner.
10. In gas generating apparatus, a producer comprising a generating chamber constructed to contain a fuel bed of ignited car- bonaceous material, a blast inlet in said gen- 130

- erating chamber and a gas outlet therefrom, a delivery main connected to said outlet, a pump in said delivery main for drawing a blast of air and moisture into the generating chamber, withdrawing the generated gas from said chamber and forcing it under pressure to a work device, means for operating said pump; a pipe having a constant orifice therein, opening from the delivery main beyond the pump, a burner connected to said pipe, at which any gas passing through said pipe may be burned, a temperature responsive device associated with said burner, and means actuated by said temperature responsive device for controlling the pump operating means to regulate the blast passing through the fuel bed to accord with the heat generated at the burner by the burning gas.
11. In gas generating apparatus, a generating chamber constructed to contain chemically active material, means for introducing into said generating chamber a second material adapted to react with the said first named material to generate a gas, and means for separating a portion of the

generated gas which is proportional to variations in the pressure of said generated gas, and controlling the said introducing means in accordance with the composition of such separated portion.

12. The method of generating a gas which consists in maintaining a body of chemically active material within a generating chamber, bringing a second material adapted to react with said chemically active material into contact therewith to effect the generation of gas, withdrawing the generated gas from said generating chamber, separating a portion of the generated gas which is proportional to variations in the pressure of such generated gas, and controlling the introduction of the said second material in accordance with the composition of such separated portion.

45
In testimony whereof I hereto affix my signature.

THOMAS CURETON.
